A. O. Bishop,

INVENTOR

Victor J. Evans

ATTORNEY

UNITED STATES PATENT OFFICE.

ARTHUR O. BISHOP, OF TAMPA, FLORIDA.

CONCEALED PULLEY AND CORD FOR SASHES.

Application filed October 2, 1926. Serial No. 139,114.

This invention relates to pulleys designed for use upon window frames for guiding sash cords thereover.

The invention embodies among other characteristics flange members carried upon the ends of the pulley mounting adapted for engagement with the window frame to obviate the use of fastening elements.

A further object of the invention comprehends the disposition of said pulleys at appropriate points within the window-frame behind the side rails of the sashes to exclude the same from view and to prevent the ingress of drafts therethrough.

With the above and other objects in view, the invention further consists of the following novel features and details of construction to be hereinafter more fully described, illustrated in the accompanying drawings, and pointed out in the appended claim.

In the drawing:

Figure 1 is an elevation of the window and sashes therefor partly broken away to illustrate the construction and application of the invention when used in conjunction therewith.

Figure 2 is an end elevation of the window frame and pulleys carried thereby.

Figure 3 is a perspective of the aforementioned pulleys.

Figure 4 is a similar view of a single pulley and mountings therefor utilized for guiding and training said sash cord to and from the aforementioned pulley.

Referring to the drawing in detail, where-in like characters of reference denote corresponding parts, the reference character 10 indicates a window frame having upper and lower sashes 11 and 12 slidably mounted within sash grooves 12'.

The invention contemplates slotted ferrules 13 carried within the side rails of the sashes adjacent the intersections of bottom rails therewith to receive the lower knotted ends of sash cords, such as indicated at 14.

Grooved companion pulley wheels 15 are journaled in spaced aligned relation between elongated supporting plates 16. Said plates are positioned within cutouts or openings provided in the grooves for the sashes and which terminate at their inner ends in oppositely disposed flange portions 17 lying flush with said grooves. The innermost of the

pulley wheels is disposed wholly within the window frame adjacent said grooves. The 55 remaining end of the plates are disposed upwardly and obliquely from said flange portions 17 and terminate to provide an abutment 18 adapted to lie flush with the opposed side of the window frame in con- 60 tra-distinction to the flange portions 17.

The sash cord 14, is then passed over the first mentioned pulley and beneath the second mentioned pulley and extended upwardly therefrom and trained over a single 65 pulley 19 of similar construction and journaled between spaced ears 20 carried by a plate member 21. Said plate 21 is mounted upon the corresponding side of the window frame with respect to the abutment 18 70 through the instrumentality of a fastening element, not shown, passed through an opening 22 in one end while the opposed end thereof provides inwardly disposed teeth 23 which are driven within the particular portion of said frame. Obviously, sash weights, such as indicated at 24, are tied upon the remaining extremities of the sash cords.

Either of the sashes, whether they be 80 moved to open or closed positions exclude the pulleys and openings, through which the same are mounted, from view thereby obviating any possibility of the ingress of drafts therethrough. The arrangement of 85 the pulley wheels 15 and the manner of training the sash cords thereover will also prevent, to a marked degree, any apparent difficulty generally experienced by the sash cords riding out of the grooves of the 90 pulleys.

The invention is susceptible of various changes in its form, proportions, and minor details of construction, and the right is herein reserved to make such changes as 95 properly fall within the scope of the appended claim.

Having thus described my invention, what is claimed is:

A sash balance comprising a frame provided with outwardly and upwardly inclined openings located within sash grooves therefor, plates carried within the openings being provided with laterally oppositely and outwardly disposed flange portions upon the 105 lower ends thereof and lying flush within

the bottoms of the grooves, the remaining portions of the plates being extending upwardly and obliquely from the flange portions, an abutment common to the plates being adapted for engagement with the outer sides of the grooves, and pulleys journaled between the plates adapted to train sash

cords thereover to force the flange portions and abutments against the sides and bottoms of the grooves to prevent displacement of the plates.

In testimony whereof I affix my signature.

ARTHUR O. BISHOP.
